UNITED STATES PATENT OFFICE.

GIOVANNI DE SANCTIS, OF HUBBARD, OHIO.

SHOE JACK.

Application filed October 7, 1922. Serial No. 593,147.

To all whom it may concern:

Be it known that I, GIOVANNI DE SANCTIS, a subject of the King of Italy, residing at Hubbard, in the county of Trumbull and State of Ohio, have invented certain new and useful Improvements in Shoe Jacks, of which the following is a specification.

This invention relates to certain new and useful improvements in shoe jacks and has particular reference to a stand carrying a cross head for supporting shoe lasts that are capable of being shifted to various positions to facilitate operation upon a shoe supported on the last.

10 The primary object of the invention resides in the provision of a shoe jack that is vertically adjustable to permit a person to use the same while either sitting or standing.

A further object of the invention is to provide a shoe jack embodying a standard supporting a forked head, each end of which is fashioned for vertically and horizontally supporting a last supporting block to facilitate convenient operation upon a shoe.

25 A still further object of the invention resides in the provision of a shoe jack of the type above set forth wherein a bracket arm is positioned between the toe portion of a shoe last and the adjacent end of the forked head for rigidly supporting the toe portion of the last while working thereon while an adjustable strap may extend from the jack stand and the shoe last or the shoe last and the adjacent portion of the forked head.

30 The invention further embodies detail improvements in a shoe jack of the type above set forth, such as devices for anchoring the shoe last to the jack and other adjustable devices.

40 With the above general objects in view and others that will appear as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

50 Figure 1 is a side elevational view of a shoe jack constructed in accordance with the present invention showing the forked head supported on the jack standard and the removable section of the jack standard for varying the height of the forked head,

Figure 2 is a side elevational view of the jack, partly in section showing the manner of mounting one of the last supporting blocks in the forked head,

Figure 3 is a fragmentary detail sectional view showing the last mounted upon the block and anchored to the fork head,

Figure 4 is a detail sectional view taken on line IV—IV of Fig. 1 showing the last vertically supported upon the upper end of the forked head,

Figure 5 is a fragmentary detail sectional view showing one end of the forked head laterally shifted to permit rotatable adjustment thereof,

Figure 6 is a detail sectional view taken on line VI—VI of Fig. 5, and

Figure 7 is a detail sectional view taken on line VII—VII of Fig. 1 showing the adjustment for the strap that anchors the shoe last to the vertical standard.

Referring more in detail to the accompanying drawings there is illustrated a shoe jack embodying a standard including a base portion 1 having a post 2 detachably mounted thereon, the upper end of the post supporting a forked or cross head 3 having perpendicularly extending end portions 4 shown more clearly in Fig. 1.

Each end portion 4 of the cross head 3 carries a pivotally mounted hinge 5 hinged upon the horizontal pins 6 shown more clearly in Figs. 2 and 5, the pins 6 being laterally positioned relative to the end portion 4 of the cross head, one side of the pivoted head 5 being cut away as at 7 to constitute a seat for the pivotally mounted locking plate 8 for retaining the pivoted head 5 perpendicularly positioned as shown in Fig. 1. The head 5 supports a block 9, the head 5 being provided with a longitudinally extending bore 10 to accommodate the passage of the screw bolts 11 formed integral with the block 9 as shown in Fig. 5, the inner end of the screw bolt 11 having a nut 12 threaded thereon that is operated by the key 13, access to the nuts 12 being obtained when the head 5 is pivotally shifted to the position shown in Fig. 5. It is to be understood that the block 9 may be rotatably adjusted relative to the head 5 and cross head 3, the adjacent faces of the end portion 4 of the cross head, and the pivotally mounted head 5 being cut away to provide a clearance for the nuts 12.

The block 9 is enlarged at its upper end 110

and is fashioned to carry a laterally or vertically positioned shoe last, the upper end of the block adjacent one edge thereof being provided with a perpendicular threaded bore 14 communicating with an enlarged pocket 15 opening at each side of the head 9 as shown in Figs. 1 and 4. The last 16 carries a screw bolt 17 projecting from the ankle portion thereof and freely extends through 10 the spacing member 18 that carries at the lower end thereof an externally threaded nipple 19 engaging the threaded bore 14 of the block 9, a nut 20 being positioned in the block pocket 15 for engagement with the 15 adjacent threaded end of the bolt 17 for anchoring the last 16 to the block 9 at the desired angular position, the nut 20 being operable from opposite sides of the block 9 as will be readily understood from an 20 inspection of Figs. 1 and 4 of the drawing. The outer end of the block 9 is also provided with a transverse internally threaded bore 21 within which the threaded extension 19 of the spacing member 18 may be positioned 25 as shown in Fig. 3, the screw bolt 17 carried by the last 16 freely extending through the spacing member and its extension to be engaged by the internally threaded cup-shaped nut 22 freely extending into the opposite 30 end of the bore 21, thereby permitting a lateral support for the last 16 for convenient operation thereon.

When a shoe S as shown in Fig. 1 is mounted upon the last 16, the toe portion of 35 the shoe and last are further braced and supported by the bracket arm 23 carrying a head 24 at its upper end for supporting the shoe, the lower end 25 of the bracket arm being received in the perpendicular opening 26 provided in the laterally projecting lug 27 carried by the block 9 as clearly shown in Figs. 1 and 4. The shoe S is further braced and anchored at the toe portion thereof on the bracket arm 23 by the belt or strap 40 45 50 55 having the looped portion thereof overlapping and enclosing the toe portion of the shoe, the other end of the strap being associated with a key 29 carrying a rectangular extension 30 as shown in Figs. 1 and 7 for reception in the rectangular socket 31 formed in the perpendicular post 2 as shown in Figs. 1 and 2. The laterally projecting lug 27 carried by the block 9 is further provided with a horizontal rectangular opening 32 into which the pin extension 31 may be received as shown by dotted lines in Fig. 1.

From the above detailed description of the device, it is believed that the construction and operation thereof will at once be apparent, it being noted that the shoe jack as illustrated in Figs. 1 and 2 may have the perpendicular post section 2 removed therefrom to permit use of the jack while the operator is in a sitting position. The pivot- 60 65 al mounting of the head 5 upon each end

portion 4 of the cross head 3 permits the desired adjustment of the block 9 that supports the shoe last, the block being rotatably adjustable upon the head 5 through the medium of the screw bolt 11 formed integral 70 with the block and the nut 12 associated with the lower projecting end thereof as shown in Fig. 5. The outer or upper ends of the blocks 9 are also constructed to provide for either a perpendicular or lateral support 75 for the shoe last as shown in Figs. 3 and 4, while the bracket arm 23 and belt 28 maintain the shoe S rigidly positioned during operation thereon.

While there is herein shown and described the preferred embodiment of the present invention, it is nevertheless to be understood that minor changes may be made therein without departing from the spirit and scope thereof as claimed.

What is claimed as new is:—

1. In a shoe jack, a stand, a cross head carried thereby, a block rotatably adjustable on each end of the cross head, and constructed to support a last in either vertical or horizontal position, the vertical support including a spacing member having an axial bore and threaded to the block, said block having a laterally opening pocket communicating with the lower end of the member bore, a last having a threaded bolt extending through said bore into the pocket and a nut secured to the end of the bolt.

2. In a shoe jack, a stand, a cross head carried thereby, a block rotatably adjustable on each end of the cross head, and constructed to support a last in either vertical or horizontal position, each end of the cross head carrying a head pivotally mounted thereon for supporting the block and a hinged plate carried by the cross head cooperating with pivoted head for holding the same aligned with the end of the cross head,

3. In a shoe jack, a stand, a cross head carried thereby, a block rotatably adjustable on each end of the cross head, and constructed to support a last in either vertical or horizontal position, each support including a spacing member having an axial bore and threaded in the block, a screw bolt carried by the lasts, nuts on the screw bolts for anchoring the lasts to the blocks, each end of the cross head carrying a head pivotally mounted thereon for supporting the block and a hinged plate carried by the cross head cooperating with pivoted head for holding the same aligned with the end of the cross head.

4. In a shoe jack, a stand, a cross head carried thereby, a block rotatably adjustable on each end of the cross head, and constructed to support a last in either vertical or horizontal position, the vertical support including a spacing member having an ax-

- ial bore and threaded to the block, said block having a laterally opening pocket communicating with the lower end of the member bore, a last having a threaded bolt 5 extending through said bore into the pocket, a nut secured to the end of the bolt, each end of the cross head carrying a head pivotally mounted thereon for supporting the block and a hinged plate carried by the cross 10 head cooperating with pivoted head for holding the same alined with the end of the cross head.
5. In a shoe jack, a stand, a cross head carried thereby, a block rotatably adjustable on each end of the cross head, and constructed to support a last in either vertical or horizontal position, each end of the cross head carrying a head pivotally mounted thereon for supporting the block, a hinged 20 plate carried by the cross head cooperating with pivoted head for holding the same alined with the end of the cross head, said pivoted head having a bore therein, a screw bolt carried by the block extending through 25 said last named bore and a nut threaded on the end of said bolt.
6. In a shoe jack, a stand, a cross head carried thereby, a block rotatably adjustable on each end of the cross head, and constructed to support a last in either vertical or horizontal position, each support including a spacing member having an axial bore and threaded in the block, a screw bolt carried by the lasts, nuts on the screw bolts for 30 anchoring the lasts to the blocks, each end of the cross head carrying a head pivotally mounted thereon for supporting the block, a hinged plate carried by the cross head cooperating with pivoted head for holding 35 the same alined with the end of the cross head, said pivoted head having a bore therein, a screw bolt carried by the block 40
- extending through said last named bore, and a nut threaded on the end of said bolt.
7. In a shoe jack, a stand, a cross head carried thereby, a block rotatably adjustable on each end of the cross head, and constructed to support a last in either vertical or horizontal position, the vertical supporting including a spacing member having an axial bore and threaded to the block, said block having a laterally opening pocket communicating with the lower end of the member bore, a last having a threaded bolt 45 extending through said bore into the pocket, a nut secured to the end of the bolt, each end of the cross head carrying a head pivotally mounted thereon for supporting the block, a hinged plate carried by the cross head cooperating with pivoted head for holding the same alined with the end of the cross head, said pivoted head having a bore therein, a screw bolt carried by the block 50 extending through said last named bore, and a nut threaded on the end of said bolt. 55
8. In a shoe jack, a stand, a cross head carried thereby, a block rotatably adjustable on each end of the cross head, and constructed to support a last in either vertical or horizontal position, and a bracket arm 60 extending between the block and toe portion of the vertically supported last. 65
9. In a shoe jack, a stand, a cross head carried thereby, a block rotatably adjustable on each end of the cross head, and constructed to support a last in either vertical or horizontal position, a bracket arm extending between the block and toe portion 70 of the vertically supported last, and an anchor strap extending between the last and stand. 75

In testimony whereof I affix my signature.

GIOVANNI DE SANCTIS.
